UNITED STATES PATENT OFFICE.

CLARENCE CLIFFORD COX, OF VIGO, OHIO.

AUTOMATIC MARKER.

1,068,326.

Specification of Letters Patent.

Patented July 22, 1913.

Application filed August 12, 1911. Serial No. 643,722.

To all whom it may concern:

Be it known that I, CLARENCE C. Cox, a citizen of the United States, residing at Vigo, in the county of Ross and State of Ohio, have invented new and useful Improvements in Automatic Markers, of which the following is a specification.

This invention relates to planters and more particularly to marker attachments 10 for this type of agricultural implement.

One of the principal objects of the invention is to provide a marker which may be readily mounted upon the ordinary type of corn planter and be conveniently operated 15 so that the marker disk or member may be easily raised when turning at the end of the row and which also may be operated from either side of the machine.

A further object of the invention is the 20 provision of a device of this character which embodies a safety appliance adapted to prevent the marker rod from breaking when the marker member strikes an immovable object.

25 A still further object of the invention will appear as the following specific description is read in connection with the accompanying drawings which form a part of this invention in which:—

30 Figure 1 is a top plan view showing the device attached on an ordinary corn planter. Fig. 2 is a rear elevation. Fig. 3 is a detail side elevation of the machine showing the alternative position of the lever in dotted 35 lines. Fig. 4 is a detail section through the marker rod.

Referring more particularly to the drawings, 1 represents an ordinary corn planter frame which is supported upon the wheel 40 axle 2, the latter member carrying the usual covering and supporting wheels 3 secured to the rear member 4 of the frame and to an intermediate cross brace 5 are suitable bearings 6 in which a shaft 7 is journaled. This 45 shaft has its rear end turned at right angles as shown at 8 and its terminal end bifurcated as shown at 9 to receive the pivoting end 10 of a stub shaft 11. The stub shaft 11 is entered into the marker rod 12 which is in 50 the form of a pipe of any suitable cross sectional contour and carries upon its outer end a suitable marking disk 13. The shaft 7 is also journaled adjacent its right angular end in a bearing 14 which is carried by a 55 frame 15 secured to the main frame 1 and

having vertical offset ends so that it will be depressed below the main frame. These bearings are all removably mounted upon the planter and the frame 15 is similarly mounted so that the attachment may be 60 readily removed or placed upon the frame when desired. Surrounding the shaft 7 is a clamp 16 and a similar clamp 17 surrounds the tubular rod 12 and is connected to the first clamp by a link or brace rod 18. 65 This brace rod is connected to the clamp by a frangible pin 18^a, for a purpose which will be hereinafter described.

Journalized upon the shaft 7 is a bearing member 19 which is held against longitudinal movement upon the shaft by transverse pins 20 extending through said shaft. The bearing 19 is provided with a laterally extending nipple in which one end of an operating shaft 21 is journaled, the opposite 70 end of the shaft being journaled in a bearing 22 removably mounted upon the side of the main frame 1 between the legs of a locking segment 23 also secured to the frame. The end of the shaft 21 has secured thereto 80 a lever 24 which carries the usual spring locking dog 25 operated by the handle and link connection 26 and adapted to engage a notch in the center of the segment 23. The shaft 21 carries a beveled gear 27 which 85 meshes with a similar gear 28 keyed to the shaft 7 so that by raising the lever to a position where the locking dog engages the notch in the segment, the shaft 7 will be given a quarter of a revolution and the 90 marker 13 will be raised to a vertical position. By continuing the movement of the lever in the same direction or to the position shown in dotted lines in Fig. 3, the marker 95 may be positioned upon the opposite side of the machine. The pin 18^a has sufficient strength under ordinary circumstances to hold the marker rod in alignment with the extension 8. If, however, the marker should engage an immovable object, such as a stump or large rock, the pin 18^a will break and the marker rod will pivot on the extension 8, thus preventing the marker rod from breaking.

Having thus fully described the invention, what I claim is:—

In combination, a planter frame, a shaft journaled therein, a pivoted lever, a gear connection between the lever and the shaft whereby the shaft may be positively rotated 110

in either direction, a right angular end upon the shaft, a stub shaft pivoted upon said end, a marker rod on the stub shaft, a brace connected to the shaft and to the rod, the connection of the brace with the rod being a frangible one and means to lock the lever in either position.

In testimony whereof I affix my signature in presence of two witnesses.

CLARENCE CLIFFORD COX.

Witnesses:

J. W. DRUMMOND,
J. F. BROWN.
